UNITED STATES PATENT OFFICE.

DOCTOR F. OLIVER, OF OAKLAND, CALIFORNIA.

DERRICK.

SPECIFICATION forming part of Letters Patent No. 444,367, dated January 6, 1891.

Application filed August 12, 1890. Serial No. 361,830. (No model.)

To all whom it may concern:

Be it known that I, DOCTOR FRANKLIN OLIVER, a citizen of the United States, residing at Oakland, Alameda county, State of California, have invented an Improvement in Derricks; and I hereby declare the following to be a full, clear, and exact description of the same.

My invention relates to the class of derricks, and especially to those derricks adapted for use in stacking hay.

It consists in the novel construction, arrangement, and combination of parts herein-after fully described, and specifically pointed out in the claims.

The general object of my invention is to provide a simple, effective, and well-balanced derrick adapted to be readily transported, and which by reason of its peculiar boom is adapted to deposit the load upon any part of the stack desired.

Referring to the accompanying drawings for a more complete explanation of my invention, Figure 1 is a perspective view of my derrick, showing it in an elevated position. Fig. 2 is a side elevation of same, the mast being lowered to a horizontal position. Fig. 3 is a detail side view of the stop, lock, and clutch mechanism of the boom. Fig. 4 is a plan of same. Fig. 5 is a perspective view of the stop, lock, and clutch mechanism.

A is the bed-frame of the derrick.

B is a standard pivoted at its lower end to the bed-frame, so that it may turn axially.

C are braces connected at their upper ends with the standard B and at their lower ends with the bed-frame.

E is the mast, consisting of separated or spaced pieces, the lower ends of which pass down on each side of the standard B, and said mast is pivoted to the upper end of said standard at the point e, whereby the mast can turn from a horizontal to a vertical plane about said pivot, and can also turn axially with the standard.

The operation of these parts is as follows: When the derrick is being transported, the mast occupies a horizontal position, in which it is supported by the standard B and by the support D, its ends extending beyond said standard and support about an equal dis-

tance, whereby the whole device is well balanced. When about to be used, the mast is turned about the pivot e to a vertical position, in which its lower end embraces the standard B, and is secured thereto while in use by means of a removable pin e'. When in a vertical position, the mast can turn axially with the standard, and in order to render this turning automatic I provide for the tilting of the standard by mounting its lower end freely enough in its pivot to allow it to tilt. It is limited in this tilting movement by the braces C, the upper ends of which are hinged to the standard, and the lower ends are connected with the bed-frame by a sliding connection, as shown at c, and consisting of bolts from the braces seated in elongated slots in the bed-frame. This connection provides for a movement of the braces sufficient to allow the standard and mast to tilt in any direction, and yet limiting their movement, the object of the tilting being to allow the mast to turn axially automatically as the load tilts it. When the mast is elevated and the machine is ready for use, suitable guys e² are extended from its top to supports in the ground.

F is the boom. This is located between the parts of the mast freely, so that it can slide therein. It is supported by means of a rope G, which is connected at its upper end with the upper end of the boom, and thence passes to and over a pulley g in the top of the mast, and thence downwardly between the parts of said mast and under a sheave g' therein just above the boom, and down to the lower end of the boom, to which it is secured. The boom rests upon a double roller g² between the parts of the mast, and the sheave g', being just above it, serves as a top guide for said boom.

H is the hoisting-rope, the course of which is as follows: From its load end it extends upwardly to and over a pulley f in the outer or upper end of the boom, thence downwardly along said boom and through the locking device hereinafter mentioned, thence to the lower end of the boom. It thence passes around a pulley f' in said lower end, and thence upwardly to and over a pulley g², mounted within or between the roller g², and down in front of guide-pulley h between the parts of the mast, and thence downwardly through the hinge by

which the braces are connected with the standard B, and to a swinging block I at the base of said standard.

J is a stop for limiting the downward movement of the boom and defining its normal position. It consists of a yoke having its inner end freely slotted over the pin which carries sheave g' , and its sides are provided with contact-shoulders j , which bear against the edge 10 of the mast. Upon the boom is the stop K, which comes in contact with the outer end of stop J. By reason of the slotted connection of stop J with the pin of sheave g' the mast itself, through the shoulders j of said 15 stop, receives the thrust of the stop when the boom descends and its stop K comes in forcible contact with stop J.

The action of the boom is as follows: When no load is on the hoisting-rope, the boom 20 turns by gravity to its normal position, its stop K resting against stop J. Now when the load is put on the hoisting-rope and said rope is pulled upon the first effect is to simply raise the load without affecting the position of the boom, which may be heavier than the load, or preferably locked, as will be presently described; but when the load reaches the height desired and the hoisting-rope is checked by any means, as by coming chuck- 25 a-block, or otherwise arrested, the boom, if locked, being released, and the hoisting-rope being still pulled upon, the effect will be to project the boom outwardly, said boom traveling freely on its supporting-rope and between its guides, so that the load is projected 30 forwardly away from the mast to any distance desired and deposited in a suitable place upon the stack. When the load is deposited, thereby relieving the hoisting-rope, the boom 35 turns by gravity to its normal position, and the hoisting-rope descends for another load. Now in order to lock the boom, to release it when desired, and to effect projection when the load has reached any height desired, I 40 have the following device: Mounted in the stop K on the boom is a latch L, controlled by a spring l and operated by a crank l', to which a cord l² is attached and hangs down within reach of the operator. Upon the outer 45 end of stop J is a catch-shoulder j', with which the latch automatically engages under the influence of its spring when the boom returns to its normal position. Thus the boom is locked and will not be projected when the 50 load is being raised; but by pulling on cord l² the latch is raised, and the boom is then released and will be projected whenever the hoisting-rope is checked. This checking may 55 take place, as before mentioned, when the load comes chuck-a-block; but it can be checked at any point, as follows: The outer end l² of latch L is formed as a brake or clutch, which, when the latch is operated to release the boom, as described, comes down upon and 60 stops the hoisting-rope, which passes directly under it through the stops K and J, which are provided with passages for it, as shown.

The hoisting-rope, as before stated, passes down through the hinge which connects the braces with the standard. This is necessary 70 to avoid any binding of said rope when the mast swings, and I have accordingly constructed a hinge which will receive and admit the passage of the rope. This hinge consists of a socket or sleeve M, secured to the 75 braces, and a tubular pintle m, secured to the standard and fitting in the socket or sleeve. The hoisting-rope passes through the tubular pintle.

In manipulating the mast to raise or lower it a bight of the hoisting-rope is wound upon a cleat x at the base of the mast. When the mast is down, the horses may be attached to the hoisting-rope and made to raise said mast. When up, the rope may be slackened, and the 85 mast when released may be gradually lowered.

Having thus described my invention, what I claim as new, and desire to secure by Letters Patent, is—

1. In a derrick, the combination of the mast, the longitudinally-slidable boom suspended therefrom, a hoisting-rope connected with the boom for effecting its projection in the direction of its length, and an arresting device for the rope, substantially as herein described. 90

2. In a derrick, the combination of the mast having the top pulley g, sheave g' , rollers g^2 , and pulley g^3 between said rollers, the boom mounted in said mast and guided by the rollers and sheave and adapted to have a longitudinal sliding movement, said boom having pulleys in the ends thereof, the supporting-rope hung from the top pulley of the mast and connected with the ends of the boom, and the hoisting-rope carried by the boom-pulleys and guided by the mast-pulleys, whereby the projection of the boom is effected, substantially as herein described. 95

3. In a derrick, the combination of the mast, the suspended slidable boom adapted to be projected therefrom, the hoisting-rope connected with the boom for effecting the projection of the same, and a stop for limiting the return of the boom, substantially as herein described. 100

4. In a derrick, the combination of the mast, the slidable boom suspended from the mast and adapted to be projected therefrom, the hoisting-rope connected with the boom for effecting the projection of the same, the stop on the boom, and the slotted stop J, connected with the mast and having side shoulders bearing against the mast, substantially as herein described. 105

5. In a derrick, the combination of the mast, the slidable boom mounted therein, the rope G, the hoisting-rope connected with the boom, whereby the projection of the boom is effected, the latch on the boom and means for operating it, and the catch carried by the mast, whereby the boom is locked in normal position and may be released to be projected, substantially as herein described. 110

6. In a derrick, the combination of the mast,

the slideable boom, the rope G, the hoisting-rope connected with the boom for effecting the projection of the boom, the brake carried by the boom, and means for operating it to engage and arrest the hoisting-rope to aid in projecting the boom, substantially as herein described.

7. In a derrick, the combination of the mast, the slideable boom, the suspending-rope G, the stop J, carried by the mast and having a catch-shoulder, the stop K, carried by the boom, the spring-actuated latch mounted in the stop K and the crank and cord for operating it, and the hoisting-rope carried by the boom and mast and passing through the stops, said hoisting-rope being engaged by the end of the latch, substantially as herein described.

8. In a derrick, the combination of the bed-frame, the tilting standard pivoted thereto, the mast pivoted to the standard, and the

braces hinged to the standard at their upper ends and connected by a slotted connection with the bed-frame at their lower ends, substantially as herein described.

9. In a derrick, the combination of the bed-frame, the pivoted standard, the braces, the hollow hinge connecting the braces with the standard, the mast pivoted to the standard, the slideable boom carried by the mast, the suspending-rope G, and the hoisting-rope carried by the boom and passing down through the hollow hinge of the standard, substantially as herein described. 25 30

In witness whereof I have hereunto set my hand.

DOCTOR F. OLIVER.
